UNITED STATES PATENT OFFICE.

JAMES MONROE GASTON, OF LOUISVILLE, KENTUCKY.

BOLT AND NUT LOCK.

SPECIFICATION forming part of Letters Patent No. 530,766, dated December 11, 1894.

Application filed April 18, 1894. Serial No. 508,041. (No model.)

To all whom it may concern:

Be it known that I, JAMES MONROE GASTON, a citizen of the United States, and a resident of Louisville, in the county of Jefferson and State of Kentucky, have invented certain new and useful Improvements in Bolt and Nut Locks; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a representation of a side elevation of the invention applied. Fig. 2 is a front view of same with the locking device up. Fig. 3 is a perspective view of the nut. Fig. 4 is a perspective of the locking device. Fig. 5 is a perspective view of the bolt.

This invention has relation to certain new and useful improvements in combined bolts, nuts, and nut-locks, the object being to provide a threadless bolt and nut of simple and practical character, and so constructed as to enable the parts to be readily and quickly applied and adjusted.

With this object in view, the invention consists in the novel construction and combination of parts, all as hereinafter described and pointed out in the appended claims.

Referring to the accompanying drawings, it will appear that the invention comprises three parts,—a rod or bolt A, a nut B, and a locking device C, all constructed and combined in the manner now to be described.

The bolt or rod A at that end portion which is to receive the nut, is of reduced diameter, forming at *a* an inwardly offset shoulder against which the nut seats. A' is a series of segmental, longitudinal parallel ribs, formed upon the said reduced portion, said ribs having at their inner ends the square shoulders *c*, which are separated from the shoulder *a* by a space equal to the thickness of the nut, said shoulders *c* forming the outer bearing seat for the nut.

The nut B has offset from its circular unthreaded bolt opening a series of parallel groove B² corresponding in form, number, and

location to the ribs A' of the bolt, the metal portions D between said grooves forming ribs corresponding to the spaces or grooves D' between the ribs A'. The inner face of the nut is beveled or wedge-shaped, and has at its thickest edge a depending guide rib or flange E, said flange or rib having cut therein two oblique and converging grooves *e*, *e*, for the locking device C. Said locking device 60 comprises a wedge-shaped flat piece of metal, of a width about equal to that of the nut, and thickened or flanged at one end C', and cut away or slotted at its opposite end portion to embrace the bolt, forming two legs or prongs 65 F, F.

To receive the locking device, the bolt or rod A is flattened off as at *f*, upon opposite sides, forming shoulders *g*, between which and the inner face of the nut the said device seats.

The parts are applied as follows:—The nut is placed on the bolt, and down against the shoulder *a* thereof, its ribs and grooves readily passing the ribs and grooves of the bolt when brought into the proper alignment therewith. The bolt, or the nut, is then turned around a sufficient distance (a one-sixth turn when three ribs and grooves are employed) to bring the ribs and grooves of the two parts out of alignment. The locking device is then placed between the wedge-shaped face of the nut and the shoulders *f*, *f*, and is driven in tight, thus securely and rigidly locking the parts, the legs or prongs F, F, entering the oblique converging grooves *e*, *e*, which causes 85 the said prongs to converge, the metal from which the locking device is made, being sufficiently malleable for this purpose. If washers are necessary, they may be placed between the shoulders *g* and the locking device, 90 as at K.

To remove the nut, a cold chisel or other tool may be driven between the nut and the rib or flange C of the locking device.

This bolt may be used for securing fish plates, and in other places where the ordinary bolt is usually employed.

Having thus described my invention, what I claim as new, and desire to secure by Letters Patent, is—

1. The herein described threadless bolt and nut, comprising the rod or bolt having an un-

threaded reduced portion at one end forming a shoulder against which the inner face of the nut seats, a series of parallel ribs on said reduced portion separated from each other by grooves or spaces, and having shoulders at their inner ends which form the outer bearing for the nut, a nut having an unthreaded opening for said bolt and having offset grooves corresponding in form to the ribs on the bolt, and separated from each other by ribs corresponding to the spaces separating the ribs on the bolt, and a locking device for securing said parts, substantially as specified.

2. A threadless bolt having an unthreaded nut-receiving portion of reduced diameter, forming an inwardly offset shoulder a , against which the nut seats, and a series of longitudinal parallel ribs A' upon the said reduced portion, the inner ends of said ribs being separated from the shoulder a , by a space substantially equal to the thickness of the nut which seats thereon, substantially as specified.

3. A threadless bolt having thereon a series of parallel segmental ribs A' , a shoulder a , and a nut seat between said shoulder a and the said ribs, in combination with a nut having grooves offset from its opening, said nut having a beveled inner face, and a locking device seating between said beveled face and shoulders on the said bolt, substantially as specified.

4. In a threadless bolt and nut device, the nut having an unthreaded bolt opening there-through, a series of segmental grooves offset from the inner circumference of said opening, said grooves extending parallel with the axis

of said opening, the inner face of said nut being beveled, and a rib or flange upon said beveled face, notched to receive a locking device, substantially as specified.

5. The combination with the threadless bolt A , having the shoulder a , the parallel, segmental ribs A' , separated by grooves, and a nut seat between the shoulder a and the inner ends of said ribs, of the nut having the unthreaded bolt opening, the parallel grooves offset from said opening, and corresponding to the said ribs A' of the bolt, the ribs between said grooves corresponding to the grooves between the ribs A' , the beveled inner face, and the rib on said face having the oblique converging notches therein, and a locking device slotted at one end portion to receive the bolt and having prongs at each side of the slot arranged to engage the said converging notches, substantially as specified.

6. In combination, an unthreaded bolt having a nut seat thereon, and a series of parallel ribs, a nut having a series of grooves to pass said ribs, and a beveled inner face formed with a notched rib, and a locking device having a wedge surface for engagement with the beveled face of the nut, and prongs for engaging the said notched rib, substantially as specified.

In testimony whereof I affix my signature in presence of two witnesses.

JAMES MONROE GASTON.
